SURFACE ACTIVE MATERIALS

Charles F. H. Allen and Charles V. Wilson,
Rochester, N. Y., assignors to Eastman Kodak
Company, Rochester, N. Y., a corporation of
New Jersey

No Drawing. Application February 29, 1940, Se-
rial No. 321,599. In Great Britain March 30,
1939

2 Claims. (Cl. 260—290)

This invention relates to surface active materials and more particularly to cationic surface active materials and particularly to surface active materials of the cationic ammonium salt type.

During the past several years, a number of surface active materials have been found. These materials may be classified as anionic, cationic, or non-ionic, depending upon whether or not they are ionizable substances, and if so, whether the anion or the cation is surface active. A number of these surface active materials have dispersing or wetting properties and have come to be known as dispersing and wetting agents.

Some of these known surface active materials (also known as capillary active materials, lipophyle materials or materials which possess interface modifying properties) which are cationic and of the ammonium salt type are quite soluble in water, and while possessing high surface activity in most cases, they are frequently difficult to obtain in a pure condition which is desirable for certain purposes, such as incorporation of the surface active materials in photographic emulsions (as described in the copending application of Burt H. Carroll, Serial No. 321,595, filed of even date herewith), now U. S. Patent 2,271,623, dated February 3, 1942.

We have now found that the known cationic surface active ammonium salts can be converted into perchlorates. In this form the materials are readily isolated from reaction mixture and are frequently obtained in the crystalline state. In the crystalline state, the agents are generally white in appearance and have sharply defined melting points. Conversion to the perchlorates is accompanied by a diminution of surface active characteristics.

For the most part, the anions occurring in the known cationic surface active ammonium salts are halides, sulfate, alkylsulfate, toluenesulfonate, nitrate and carboxylic acid anions, e. g. formate and acetate. We have found it advantageous to convert these known salts to the perchlorates by treating an alcoholic or aqueous solution of the known salt with a water-soluble perchlorate, e. g. sodium or potassium perchlorate or perchloric acid. Alcohols which are completely miscible with water are advantageously employed, e. g. methyl or ethyl alcohol.

The following examples will serve to illustrate the preparation of our new cationic surface active ammonium salts. These examples are not intended to limit our invention. The parts given in the following examples are parts by weight.

EXAMPLE 1.—*N-(n-nonyl)-pyridinium perchlorate*

647 parts of n-nonyl-p-toluenesulfonate and 175 parts of pyridine were mixed together and heated at 125° to 140° C. for three hours, under reflux. Upon cooling the reaction product, it solidified. 413 parts of this crude *N-(n-nonyl)-*

pyridinium p-toluenesulfonate were dissolved in 750 parts of warm methyl alcohol. To the resulting dark solution was added a warm aqueous solution of sodium perchlorate (270 parts in 200 parts of water). Upon chilling the resulting mixture for a short time, the pyridinium perchlorate separated out. It was filtered off and dried in the air. 312 parts (91% yield) of the pyridinium perchlorate as white crystals melting at 79° C. were obtained.

The n-nonyl-p-toluenesulfonate employed in the above example can be prepared according to the method for preparing lauryl-p-toluenesulfonate described in the *Jour. Am. Chem. Soc.* 55, 15 347 (1933).

EXAMPLE 2.—*N-(n-heptylthiomethyl)-pyridinium perchlorate*

6 parts n-heptylthiomethyl chloride (prepared by treating an equimolecular mixture of n-heptyl mercaptan and formaldehyde with a molecular equivalent of hydrogen chloride, at 0° to 10° C.) and 2.7 parts of pyridine were mixed together and warmed for 15 minutes on the steam bath. The development of a slight color and an increase in viscosity of the reaction mixture indicated the formation of *N-(n-heptylthiomethyl)-pyridinium chloride*.

The viscous syrup, thus prepared, was dissolved in 25 parts of methyl alcohol at 40° to 50° C. To the warm methyl alcoholic solution were added 5 parts of sodium perchlorate, dissolved in 10 parts of water. On chilling the resulting mixture, 9 parts of *N-(n-heptylthiomethyl)-pyridinium perchlorate* separated out in the form of fine, white, silky needles, melting at 89° C.

In a similar manner, n-heptylthiomethylidemethylbenzylammonium perchlorate, melting at 167° C. and n-dodecylthiomethyl-pyridinium perchlorate, melting at 114° to 115° C. were prepared.

EXAMPLE 3.—*N-(n-heptoxyethyl)-pyridinium perchlorate*

176 parts of n-heptoxyethyl chloride (prepared by treating an equimolecular mixture of n-heptyl alcohol and formaldehyde with a molecular equivalent of hydrogen chloride at 0° to 10° C.) and 90 parts of pyridine were mixed together. A reaction took place immediately, considerable heat being evolved. The crude *N-(n-heptoxyethyl)-pyridinium chloride* thus formed was cooled and dissolved in 400 parts of warm methyl alcohol. To the warm methyl alcoholic solution was added a warm aqueous solution of sodium perchlorate (150 parts dissolved in 190 parts of water). On chilling the resulting mixture, 253 parts of the *N-(n-heptoxyethyl)-pyridinium perchlorate* separated out as white crystals, melting at 71° to 73° C.

In a similar manner, the following pyridinium

erchlorates were prepared from pyridinium chlorides:

	M. P., °C.
- (n-hexoxymethyl)-pyridinium perchlorate	66
- (n-octoxymethyl)-pyridinium perchlorate	82
- (n-nonoxyethyl)-pyridinium perchlorate	72
- (n-decoxyethyl)-pyridinium perchlorate	102
- (n-undecoxymethyl)-pyridinium perchlorate	70
- (β-cyclohexylethoxymethyl)-pyridinium perchlorate	68-70
N - (β - phenylethoxymethyl) - pyridinium perchlorate	oil
N-citronelloxymethylpyridinium perchlorate	oil
N-geranioxymethylpyridinium perchlorate	20
N-cinnamylloxymethylpyridinium perchlorate	25
N-rhodinoxymethylpyridinium perchlorate	oil
N-(3,7-dimethyloctanoxyethyl)-pyridinium perchlorate	25
N-abetylloxymethylpyridinium perchlorate	oil
N-(γ-phenyl-n-propoxymethyl) - pyridinium perchlorate	oil
N-(β-n-amyloxyethoxymethyl)-pyridinium perchlorate	85-86
N-sandaloxymethylpyridinium perchlorate	31-34

The pyridinium chlorides employed to prepare the foregoing perchlorates were prepared as illustrated in Example 3 by mixing pyridine with the appropriate oxymethyl chloride. The oxymethyl chlorides were always prepared by treating an equimolecular mixture of the appropriate alcohol (e. g. n-hexylalcohol, β-cyclohexylethylalcohol, citronellol, rhodinol, abetyl alcohol or β-n-amyloxyethyl alcohol) and formaldehyde with a molecular equivalent of hydrogen chloride, at 0 to 10° C. In the case of Sandaloxymethyl chloride, the alcohol involved is actually a mixture of alcohols, viz. those occurring in Sandalwood oil. Where the perchlorate obtained is an oil at ordinary temperatures, it was purified by extracting impurities therefrom with diethyl ether and driving off residual ether by warming the oil.

EXAMPLE 4.—n-Heptoxydimethylbenzylammonium perchlorate

To 85 parts of dimethylbenzylamine were added 100 parts of n-heptoxyethyl chloride. The mixture became quite hot. It was stirred and allowed to cool to room temperature. The thick viscous syrup thus obtained was essentially n-heptoxydimethylbenzylammonium chloride.

This viscous syrup was dissolved in 125 parts of warm methyl alcohol and to the warm alcoholic solution was added a warm aqueous solution of sodium perchlorate (150 parts dissolved in 100 parts of water). An oil separated at once and some sodium chloride precipitated. Sufficient water was added to redissolve the sodium chloride. The oily layer was separated from the aqueous layer. The oily layer was shaken with diethyl ether to remove unchanged amine and unchanged n-heptoxyethyl chloride. The oily product was separated from the ether and then

heated in an open dish on the steam bath for about 2 hours to remove ether and methyl alcohol. 200 parts of an oil which is essentially n-heptoxydimethylbenzyl ammonium perchlorate were thus obtained. Upon chilling to 0° C., the oil set to a viscous mass.

In a similar manner, the following ammonium perchlorates were obtained:

	M. P., °C.
10 n-Nonyldimethylbenzylammonium perchlorate	65
n - Heptoxydimethylbenzylammonium perchlorate	oil
n-Nonyldiethylbenzylammonium perchlorate	oil
p - ter - Butylphenoxyethoxyethylbenzylammonium perchlorate	oil

EXAMPLE 5.—N-carbo-n-nonoxyethylpyridinium perchlorate

5 parts of n-nonylchloracetate (prepared by treating chloracetic acid with n-nonyl alcohol) and 2 parts of pyridine were placed in 25 parts of dry benzene and the solution was heated on a steam bath, under reflux, for 18 hours. The solution became very dark and the N-carbo-n-nonoxyethylpyridinium chloride failed to crystallize out upon cooling the solution. The solvent benzene was removed by distillation on the steam bath.

The residue from the aforesaid steam distillation, consisting essentially of crude N-carbo-n-nonoxyethylpyridinium chloride, we dissolved in 20 parts of methyl alcohol. To the methyl alcoholic solution was added 4 parts of sodium perchlorate dissolved in 10 parts of water. Upon chilling the resulting mixture, 2.3 parts of the pyridinium perchlorate, as a yellow flaky salt, separated out. It melted at 92° C.

In a similar manner, γ-(γ-phenylbutyroxy)-propylpyridinium perchlorate, melting above 200° C., was prepared. The γ-(γ-phenylbutyroxy)-propylpyridinium chloride employed to prepare this perchlorate was prepared by the interaction of pyridine γ-chloro-n-propyl-γ-phenylbutyrate which was formed by the interaction of γ-phenylbutyryl chloride and 1,3-propylene chlorohydrin.

EXAMPLE 6.—N-(β-caproxyethyl)-pyridinium perchlorate

4.5 parts of β-chloroethyl caproate (prepared by the interaction of caproyl chloride and ethylene chlorohydrin) were mixed with 2 parts of pyridine and the mixture was heated for 2 hours at 125° to 135° C., under reflux. On cooling the reaction mixture, a viscous mass of crude N-(β-caproxyethyl)-pyridinium chloride was obtained.

This crude pyridinium chloride was dissolved in 15 parts of methyl alcohol and to the methyl alcoholic solution were added 5 parts of sodium perchlorate dissolved in 10 parts of warm water. Upon chilling the resulting solution, an oil separated. The oily layer was removed and washed with diethyl ether to remove unchanged reactants. The oil was then heated on the steam bath to remove residual ether. The resulting oil was essentially N-(β-caproxyethyl)-pyridinium perchlorate.

EXAMPLE 7.—N-(n-butoxyethoxyethyl)-pyridinium perchlorate

3.1 parts of n-butoxyethoxyethyl chloride (prepared from "Butyl Carbitol" and phosphorous pentachloride according to the method of P. Iomaa and Kenetti, Ber. 64, 798, (1931)) and 1.5

parts of pyridine were mixed together and heated, under reflux, for 3 hours at 125° to 135° C. Upon cooling, a viscous mass resulted which was essentially N-(n-butoxyethoxyethyl)-pyridinium chloride.

The aforesaid pyridinium chloride was dissolved in 15 parts of warm methyl alcohol and to the warm alcoholic solution, 2.5 parts of sodium perchlorate, dissolved in 10 parts of warm water, were added. After chilling to 0° C. for several hours, an oily layer separated. The oily layer was removed from the aqueous layer and washed with diethyl ether to remove unchanged reactants. The oil was then heated on a steam bath to remove residual ether. The oil thus obtained was essentially N-(n-butoxyethoxyethyl)-pyridinium perchlorate.

EXAMPLE 8.—N-(p-ter-butylphenoxyethoxyethyl)-pyridinium perchlorate

25.6 parts of p-ter-butylphenoxyethoxyethyl chloride (prepared by reacting one molecular proportion of p-ter-butylphenol with four molecular proportions of β,β' -dichloroethyl ether at 160° to 180° C. for 10 to 15 hours, in the presence of solid sodium hydroxide, according to the method given in Jour. Am. Chem. Soc. 47, 1174, 1925) and 8 parts of pyridine were mixed together and heated, under reflux, on an oil bath at 125° to 135° C. for 3 hours. On cooling, the reaction mass solidified.

The aforesaid solid mass was dissolved in 50 parts of methyl alcohol and to the alcoholic solution were added 17 parts of sodium perchlorate dissolved in 20 parts of warm water. Upon cooling the resulting mixture, 23 parts of the pyridinium perchlorate separated out as a white flaky crystalline material, melting at 64° to 69° C.

In a similar manner, the following related perchlorates were obtained:

	M. P. °C.
4-methyl	63-64
4-ethyl	oil
4-isopropyl	133
4-ter-amyl	oil
4-cyclohexyl	105
2,4-dimethyl	oil
3-methyl-6-isopropyl	78-80
2-methyl-5-isopropyl	87-89
2-phenyl	oil
4-phenyl	134
2-benzyl	135
4-benzyl	67
2-hydroxymethyl	146-147
4-chloro	79
2,4-dichloro	88-90
4-bromo	61-63
2-iodo	75
4,4'-chlorophenyl	79-81
2-isopropyl-5-methyl-4-chloro	88
4-methoxy	62-64
4-aceto	98
4-propio	70
4-n-butyro	69
4-allyl-2-methoxy	61-63
2-carboxy	oil
4-phenylazo	124-126
	105-107

EXAMPLE 9.—N-(p-formylphenoxyethoxyethyl)-pyridinium perchlorate

2.5 parts of p-formylphenoxyethoxyethyl chloride (prepared by reacting one molecular proportion of p-hydroxybenzaldehyde with four molecular proportions of β,β' -dichloroethyl ether at 160° to 180° C. for 10 to 15 hours, in the presence of solid sodium hydroxide) and 1 part of pyridine were mixed together and heated, under reflux, on an oil bath for 3 hours at 130° to 140° C. Upon cooling, the reaction mixture set to a viscous gum.

This gummy product was dissolved in 10 parts of warm methyl alcohol and to the methyl alcoholic solution were added 2 parts of sodium perchlorate dissolved in 6 parts of water. Upon chilling the resulting mixture to 0° C. for several hours, 2.3 parts of the pyridinium perchlorate separated out as pale yellow crystals melting at 105° C.

In a similar manner, the following perchlorates were obtained:

	M. P. °C.
3-formyl	104-106
2-methyl-4-formyl-5-isopropyl	106
2-isopropyl-4-formyl-5-methyl	97
2-methoxy-4-formyl	153
2-ter-amyl-4-formyl	oil
2-formyl-4-chloro	88-90
2-formyl-4-bromo	56

EXAMPLE 10.—N-(β -naphthoxyethoxyethyl)-pyridinium perchlorate

50.4 parts of β -naphthoxyethoxyethyl chloride (prepared by reacting one molecular proportion of β -naphthol with four molecular proportions of β,β' -dichloroethyl ether at 160° to 180° C. for 10 to 15 hours, in the presence of solid sodium hydroxide) were mixed with 18 parts of pyridine and the mixture heated at 120° to 125° C. for 14 hours. The reaction product was cooled, washed with diethyl ether and then dissolved in 250 parts of methyl alcohol. To the methyl alcoholic solution were added 40 parts of sodium perchlorate dissolved in 250 parts of warm water. The resulting mixture was allowed to stand in an ice chest for 5 hours, when an oil separated which quickly solidified upon stirring. The solid pyridinium perchlorate was filtered off and washed with diethyl ether. It melted at 78° to 81° C.

In a similar manner, N-(α -naphthoxyethoxyethyl)-pyridinium perchlorate and 2(3)-phenanthroxyethoxyethyl-pyridinium perchlorate were obtained. Each was obtained as an oil.

EXAMPLE 11.—N-(p-methylphenoxypropoxypropyl)-pyridinium perchlorate

6.5 parts of p-methylphenoxypropoxypropyl chloride (prepared by reacting one molecular proportion of p-cresol with four molecular proportions of γ,γ' -dichloro-di-n-propyl ether at 160° to 180° C. for 10 to 15 hours, in the presence of solid sodium hydroxide) and 2.5 parts of pyridine were mixed and heated, under reflux, at 125° to 135° C. for 3 hours. Upon cooling, the reaction product was taken up in 15 to 20 parts of methyl alcohol. To this solution, were added 6 parts of sodium perchlorate dissolved in 12 parts of water. The pyridinium perchlorate separated as an oil

which solidified after chilling at 0° C. for several hours. The pyridinium perchlorate was recrystallized from ethyl alcohol and 7 parts of a white crystalline salt, melting at 64° to 65° C., were obtained.

In a similar manner, N-(p-phenylphenoxypropoxypropyl)-pyridinium perchlorate, melting at 100° C., and N-(ter-butylphenoxypropoxypropyl)-pyridinium perchlorate, an oil, were obtained.

EXAMPLE 12.—N-(p-cresylthioethoxyethyl)-pyridinium perchlorate

6.3 parts of p-cresylthioethoxyethyl chloride were prepared by reacting one molecule proportion of thiocresol with four molecular proportions of 15 3'-dichlorodiethyl ether at 160° to 180° C. for 10 to 15 hours, in the presence of solid sodium hydroxide) and 3 parts of pyridine were mixed together and heated at 125° to 135° C. for 3 hours, under reflux. The reaction product was 20 cooled and taken up in about 20 parts of warm methyl alcohol. To this warm solution were added 6 parts of sodium perchlorate, dissolved in 2 parts of water. The pyridinium perchlorate separated as an oil which solidified upon chilling for several days at 0° C. The crude material was recrystallized from methyl alcohol and 5 g. of a white crystalline salt, melting at 45° to 46° C. were obtained.

EXAMPLE 13.—N-(ω -phenyltetraoxoethyl)-pyridinium perchlorate

4.5 parts of ω -phenyltetraoxoethyl chloride prepared by reacting one molecular proportion of phenol with four molecular proportions of 35 tetraethylene glycol dichloride at 160° to 180° C. for 10 to 15 hours, in the presence of solid sodium hydroxide) and 1.8 parts of pyridine were mixed together and heated, under reflux, at 125° to 135° C. for three hours. The reaction mixture was cooled and taken up in 20 parts of methyl alcohol. To the resulting methyl alcoholic solution, 5 parts of sodium perchlorate, dissolved in 10 parts of water, were added. The pyridinium perchlorate separated as an oil which did not solidify even upon several weeks chilling at 0° C. The oil was washed several times with diethyl ether and then heated on a steam bath to remove traces of ether. The oil still failed to solidify upon prolonged chilling at 0° C.

EXAMPLE 14.—N,N'-decamethylene-bis-N-methyl-piperidinium perchlorate

5 parts of decamethylene bromide and 3.5 parts of N-methylpiperidine were mixed together and heated for a few minutes in an oil bath at 150° C. A vigorous reaction ensued and the mixture became solid.

The solid product was dissolved in 20 parts of warm methyl alcohol and to the warm alcoholic solution were added 5 parts of sodium perchlorate dissolved in 10 parts of warm water. Upon chilling the resulting mixture at 0° C. for several hours, 3 parts of the piperidinium perchlorate separated out as white crystals. The crystals melted at 186° to 190° C.

EXAMPLE 15.—M-n-nonyl-2-phenylpyrimidazolium perchlorate

Five and seven-tenths parts of 2-phenylpyrimidazole and 9 parts of n-nonyl p-toluenesulfonate were heated for 3 hours at 140-150° C. and cooled. The N-n-nonyl-2-phenylpyrimidazolium p-toluenesulfonate separated as an oil.

The oily product was washed with diethyl ether and dissolved in 30 parts of hot methyl alcohol. To this hot methyl alcoholic solution, 15 parts of sodium perchlorate in 15 parts of warm water was added. On cooling the resulting solution, 13.5 parts of the crude perchlorate melting at 82-86° separated. When the salt was recrystallized from methyl alcohol, the purified perchlorate melted at 98-100° C. The salt has the following formula:

EXAMPLE 16.—N-(ω -hydroxydecyl)-pyridinium perchlorate

12.2 parts of decamethylene chlorohydrin and 5.6 parts of pyridine were mixed together and the mixture was heated, under reflux, in an oil bath for 3 hours at a temperature of 125° to 135° C. Upon cooling the mixture, it set to a white cake which was then dissolved in 25 parts of warm methyl alcohol. To the resulting solution, diethyl ether was added until a cloudiness developed. Upon chilling the resulting cloudy solution to 0° C. for 2 hours, 10 parts of the pyridinium chloride separated out.

2 parts of the pyridinium chloride were dissolved in 10 parts of methyl alcohol and to the resulting solution were added 2 parts of sodium perchlorate dissolved in 8 parts of warm water. Upon chilling the resulting solution to 0° C., 1.5 parts of the pyridinium perchlorate separated out as a white solid. It melted at 51° to 52° C.

EXAMPLE 17.—N-methyl- α -(n-nonyl)-pyridinium perchlorate

142 parts of α -(n-nonyl)-pyridine and 142 parts (10% excess of methyl-p-toluenesulfonate were mixed well and allowed to stand at room temperature. An exothermic reaction took place, the temperature rose to 125° C. and the reaction mass finally solidified. The solidified mass was dissolved in 700 parts of a warm mixture of 6 parts of acetone to 1 part of methyl alcohol. Upon cooling the resulting solution, N-methyl- α -(n-nonyl)-pyridinium-p-toluenesulfonate separated out. It was collected on a filter and washed with cold acetone and dried in the air. 220 parts of faintly yellow crystals, melting at 134° C., were obtained.

32 parts of N-methyl- α -(n-nonyl)-pyridinium-p-toluenesulfonate were dissolved in 32 parts of warm methyl alcohol and to the resulting solution were added 32 parts of sodium perchlorate, dissolved in 32 parts of water. Upon chilling the resulting mixture to 0° C., 23 parts of the N-methyl- α -(n-nonyl)-pyridinium perchlorate separated out. It was filtered off, using a chilled funnel because of its low melting point.

In a similar manner, N-methyl- α -(n-heptyl)-pyridinium-p-toluenesulfonate, melting at 88° C., N-methyl- α -(n-octyl)-pyridinium-p-toluenesulfonate, melting at 116° to 118° C., N-methyl- α -(n-decyl)-pyridinium-p-toluenesulfonate, melting at 99° C., N-methyl- α -(n-undecyl)-pyridinium-p-toluenesulfonate, melting at 95° to 98° C. and N-methyl- γ -nonylpyridinium-p-toluenesulfonate, melting at 160° to 162° C. can be prepared and converted to the corresponding perchlorates.

**EXAMPLE 18.—*N* - heptoxyethyl - α -(*n*-nonyl) -
pyridinium perchlorate**

2.2 parts of α -(*n*-nonyl)-pyridine and 1.7 parts of *n*-heptoxyethyl chloride were mixed together. Heat was evolved and a gummy product resulted. The gummy product was dissolved in 10 parts of warm methyl alcohol and to the resulting solution were added 3 parts of sodium perchlorate dissolved in 10 parts of warm water. An oil separates out immediately. The oil was separated from the aqueous alcoholic layer and then dissolved in methyl alcohol. The methyl alcohol solution was treated with water until a faint cloudiness developed. The solution was then chilled to 0° C. *N*-heptoxyethyl- α -(*n*-nonyl)-pyridinium perchlorate separated out as white crystals, melting at 61° C.

**EXAMPLE 19.—*N*-methyl- α -(carbo-*n*-heptoxy) -
pyridinium perchlorate**

6.7 parts of *n*-heptyl picolinate and 5.6 parts of methyl-*p*-toluenesulfonate were mixed together and heated for 3 hours at 125° to 135° C., under reflux. The reaction mixture solidified upon cooling and was recrystallized from a small volume of acetone. The recrystallized product was washed with diethyl ether and allowed to dry. In this manner, 6.5 parts of the pyridinium-*p*-toluenesulfonate were obtained as buff crystals, melting at 108° C. A portion was converted to the perchlorate in the manner illustrated in the above example.

Similarly, the following pyridinium *p*-toluenesulfonates were prepared and converted to the corresponding pyridinium perchlorates.

	M. P. °C.
<i>N</i> - methyl - α -(carbo- <i>n</i> -octoxy) -pyridinium- <i>p</i> -toluenesulfonate	110
<i>N</i> - methyl - β -carbo- <i>n</i> -heptoxy) -pyridinium- <i>p</i> -toluenesulfonate	85
<i>N</i> - methyl - β -(carbo- <i>n</i> -octoxy) -pyridinium- <i>p</i> -toluenesulfonate	88-89
<i>N</i> - nonyl - β -(carbo- <i>n</i> -octoxy) -pyridinium- <i>p</i> -toluenesulfonate	100

**EXAMPLE 20.—*N*-methyl- α -tridecylpyridinium
perchlorate**

2.6 parts of α -(*n*-tridecyl)-pyridine and 1.4 part of methyl iodide were mixed together and allowed to stand overnight at room temperature. The resulting solid reaction product was dissolved in 10 parts of warm methyl alcohol. To this solution were added 3 parts of sodium perchlorate dissolved in 5 parts of warm water. The resulting mixture was allowed to stand in an icebox for several hours when white crystals of the pyridinium perchlorate separated out. These crystals (2.1 parts) melted at 20° C. and are advantageously filtered off using a chilled funnel.

N - (*n* - heptoxyethyl) - α -tridecyl-pyridinium perchlorate, melting at 23° C. was similarly prepared from *N*-(*n*-heptoxyethyl) - α -tridecyl-pyridinium *p*-toluenesulfonate which was obtained as a gum by the interaction of α -(*n*-tridecyl)-pyridine with methyl-*p*-toluenesulfonate.

**EXAMPLE 21.—Octyl dimethyl sulfonium
perchlorate**

Four parts of octyl dimethyl sulfonium *p*-toluenesulfonate in ten parts of warm methyl alcohol were treated with four parts of sodium perchlorate in ten parts of warm water. On cooling the resulting solution, an oil began to separate. This oil was thrown out by the addition

70 of thirty parts of water, was washed with 50% methyl alcohol-water solution, then with diethyl ether, and was dried on a steam cone. The yield of oil was three parts.

**EXAMPLE 22.—*n*-Decyl-1-phenyl-3,5-dimethyl-
pyrazolium perchlorate**

A mixture of 2.7 parts of *n*-decyl iodide and 1.7 parts of 1-phenyl-3,5-dimethylpyrazole was heated for 3 hours at 120-150° C. The reaction product was dissolved in 15 parts of methyl alcohol and treated with 3 parts of sodium perchlorate in 10 parts of water. On chilling for several hours an oil separated. It was removed from the aqueous alcoholic layer and washed with ether to remove any unchanged *n*-decyl iodide or pyrazole, and then warmed on the steam bath for a few minutes to remove volatile solvents. There was thus obtained 4 parts of a crude oily product which is essentially *n*-decyl-1-phenyl-3,5-dimethylpyrazolium perchlorate.

**EXAMPLE 23.—Tetramethylene-bis-1-phenyl-3,5-
dimethylpyrazolium perchlorate**

A mixture of 2.2 parts of tetramethylene bromide and 3.4 parts of 1-phenyl-3,5-dimethylpyrazole was heated for 3 hours at 120-150° C. The product, which was essentially tetramethylene-bis-1-phenyl-3,5-dimethylpyrazolium bromide, fails to solidify on cooling. It was dissolved in 15 parts of methyl alcohol and treated with a warm solution of 3 parts of sodium perchlorate in 10 parts of water. On chilling for several hours, the tetramethylene-bis-1-phenyl-3,5-dimethylpyrazolium perchlorate separated as an oil. It was removed from the alcoholic-aqueous layer and dissolved in 15 parts of warm acetone. On chilling this solution, 1.5 parts of tetramethylene-bis-1-phenyl-3,5-dimethylpyrazolium perchlorate separated as a white salt melting at 216-218° C.

The cationic surface active quaternary ammonium perchlorates having a cation which contains a chain of at least eight members are especially useful substances for incorporation in photographic emulsions. Advantageously, such members are from the group consisting of carbon, oxygen and sulfur atoms. One or more aromatic rings, such as a benzene ring for example, can take the place of one or more of the eight or more atoms. Thus, a benzene ring can take the place of one atom, while a naphthalene ring (two benzene rings fused together) can take the place of two atoms. The atoms attached to the eight or more atoms in the chain (where valence permits) can be hydrogen, oxygen, sulfur, carbon or halogen for example. Any aromatic ring system in the chain can carry simple substituents. The organic group containing a chain of eight or more atoms can be directly attached to the quaternary ammonium nitrogen atom or indirectly thereto by means of a group of atoms. Cationic surface active quaternary ammonium perchlorates having an ammonium cation containing a lipophilic organic group which contains a chain of from nine to twelve members selected from the group consisting of carbon atoms, oxygen atoms, sulfur atoms and aromatic ring systems are especially useful. More specifically, the *N*-alkoxymethylpyridinium perchlorates, the alkoxymethylidemethylbenzylammonium perchlorates and alkoxymethyldiethylbenzylammonium perchlorates, in which the alkoxymethyl group is one of the formula $C_nH_{2n+1}O$ wherein n represents a positive integer of from 6 to 10

are especially useful, as are the quaternary pyridinium salts characterized by having attached to one of the carbon atoms of the pyridine nucleus an organic group containing a chain of at least eight atoms.

It is, therefore, apparent from the foregoing that we have provided perchlorate derivatives of a variety of surface active materials, of which the ammonium type are prepared. Hence, we do not wish to be restricted in our invention excepting insofar as is necessitated by the prior art and the spirit of the appended claims.

What we claim as our invention and desire to be secured by Letters Patent of the United States is:

1. A cationic surface active quaternary ammonium perchlorate of the following general formula:

5

10 wherein n represents a positive integer of at least 8.

2. N-n-nonyl-2-phenylpyrimidazolium perchlorate.

CHARLES F. H. ALLEN.
CHARLES V. WILSON.

CERTIFICATE OF CORRECTION.

Patent 2,299,782.

October 27, 1942.

CHARLES F. H. ALLEN, ET AL.

It is hereby certified that error appears in the printed specification of the above numbered patent requiring correction as follows: Page 4, first column, line 14, for "molecule" read --molecular--; line 68, for "M-n-nonyl" read --N-n-nonyl--; and that the said Letters Patent should be read with this correction therein that the same may conform to the record of the case in the Patent Office.

Signed and sealed this 5th day of January, A. D. 1943.

Henry Van Arsdale,
Acting Commissioner of Patents.
